UNITED STATES PATENT OFFICE.

HENRY M. CALDWELL, OF HARTWELL, OHIO.

DESIGN FOR A BADGE.

SPECIFICATION forming part of Design No. 27,621, dated September 7, 1897.

Application filed January 30, 1897. Serial No. 621,357. Term of patent 31 years.

To all whom it may concern:

Be it known that I, HENRY M. CALDWELL, a citizen of the United States of America, residing at Hartwell, in the county of Hamilton and State of Ohio, have devised a new and original Design for Badges, of which the following is a specification, reference being had to the accompanying drawing, which shows the general outlines thereof.

10 The badge is primarily designed to indicate sympathy with the cause of Cuba; and it consists, essentially, of a ribbon representing the Cuban colors, blue and white, with a suggestion of the United States colors, fastened in 15 a bow form and carried by a gilt disk in the rear of the loop.

The drawing herewith filed is an elevation of my design.

The numeral 1 designates a disk gilded, preferably, in gold color and forming a partial background; 2, the ribbon; 3, blue stripes in the ribbon; 4, white stripes; 5, a triangular red space at one end of the bow, and 6 a five-pointed white star superposed upon the triangular red space. The disk is intended to be attached to a pin or other device for securing the badge to a coat or other garment.

What I claim is—

The design for a badge substantially as herein shown and described.

HENRY M. CALDWELL.
